UNITED STATES PATENT OFFICE.

CARL SCHRAUBSTADTER, OF BROOKLINE, MASSACHUSETTS.

DESIGN FOR TYPE.

Specification forming part of Design No. 5,493, dated January 23, 1872.

I, CARL SCHRAUBSTADTER, of Brookline, county of Norfolk and State of Massachusetts, have invented and produced a new and original Design for Printing-Types, of which the following is a specification:

The nature of my design, which I call "Tremont," is fully represented in the accompanying specimen impression, to which reference is made.

I claim as my invention—
The design for printing-types, as shown.
CARL SCHRAUBSTADTER.
